United States Patent Office

Des. 186,127
Patented Sept. 15, 1959

186,127

BRACKET FOR BOAT LIGHTS OR THE LIKE

Ralph D. Needham, Perry, Iowa

Application May 1, 1958, Serial No. 50,696

Term of patent 14 years

(Cl. D48—4)

Fig. 1.

Fig. 2.

Fig. 3.

Fig. 1 is a perspective view of a bracket for boat lights or the like showing the front and one side thereof, embodying my new design;

Fig. 2 is a front elevational view thereof; and

Fig. 3 is a top plan view thereof.

I claim:

The ornamental design for a bracket for boat lights or the like, substantially as shown.
